UNITED STATES PATENT OFFICE.

FRANK JOERGER, OF BROOKLYN, NEW YORK.

PAINTBRUSH-FERRULE AND METHOD OF MAKING THE SAME.

1,375,847.

Specification of Letters Patent. Patented Apr. 26, 1921.

Application filed February 10, 1920. Serial No. 357,501.

To all whom it may concern:

Be it known that I, FRANK JOERGER, a citizen of the United States, residing at 1007 Decatur street, Brooklyn, county of 5 Kings, and State of New York, have invented certain new and useful Improvements in Paintbrush-Ferrules and Methods of Making the Same, fully described and represented in the following specification 10 and the accompanying drawings, forming a part of the same.

This invention relates to an improved process for the manufacture of a flat brush formed of a flat tuft of bristles and connected with a round handle, and the object 15 of the invention is to furnish an improved means of securing together the flat ferrule which embraces the bristles, and the hollow shank by which the wooden handle is attached to the ferrule.

Heretofore a cap has been secured upon the ferrule in an imperfect manner so that no water-tight connection was effected and great injury has with this construction 25 resulted to the bristles when the brush was left soaking in water.

The imperfection in the union of the cap and ferrule arose from the fact that the bristles had commonly been inserted in the 0 ferrule before the cap was secured thereto, thus straining the ferrule out of its normal shape and rendering it impossible to close its upper end by a cap having a flange extended all around its margin.

A continuous flange is absolutely necessary to make a strong and uniform joint around the top end of the ferrule, and such caps in themselves could be made with perfect uniformity but could not be fitted upon the ends of ferrules when subjected to the treatment they receive in fitting the bristles therein, which, necessarily pushes the flat sides of the ferrule apart; and the cap has therefore been commonly made with a soldering flange upon two parallel sides and one end, leaving the other end 50 destitute of the flange and adapted to project over one edge of the ferrule when the cap was soldered thereon.

Such projection compensated for variations in the dimensions of the ferrule. The projecting portion is readily cut off, and this end of the cap therefore has no flange to hold it to the ferrule.

When flanges made in this defective manner were put into use any blows upon the

ferrule near the cap where the cap was destitute of the flange operated to open the joint at their junction, and permit access of water to the bristles inside when the 60 flange was soaked in water, thus causing injury to the brush.

The ferrule of the brush is frequently subjected to such strains, as when knocking the paint out of the brush by a blow 65 against the paint-pot.

To avoid this defective construction I reverse the ordinary process of manufacture and secure the cap upon the ferrule before the bristles are inserted in the ferrule, which 70 method of operation permits the manufacture of ferrules and caps of perfect uniformity and interchangeability so that the caps can be flanged around their entire margin and embrace the entire upper end of 75 the ferrule.

When such a cap is used a hollow metallic shank is attached to the center of the cap to receive the wooden handle of the paint-brush and my process of manufacture 80 permits such hollow shank to be soldered to the cap before or after it is secured upon the ferrule.

The invention will be understood by reference to the annexed drawing, in which 85 Figure 1 is a perspective view of the ferrule; Fig. 2 is a perspective view of an inverted cap with continuous flange around its margin; Fig. 3 shows the cap and ferrule secured together by soldering the flange to 90 the ferrule; and Fig. 4 is an elevation of the ferrule completed, with a hollow socket for the brush-handle secured to the cap and ferrule by soldered tongues.

a designates the lower end of the ferrule, 95 and *b* the upper end to which the cap *c* is secured by the marginal flange *c'* which is made to snugly embrace the upper end of the ferrule and be soldered thereto around the entire periphery.

With such construction the union of the cap and ferrule cannot be disturbed by any use to which a paint brush is subjected.

A wooden handle may be used with the ferrule, *d* being a hollow metal shank to 105 fit tightly upon the handle, and *f* tongues attached to opposite sides of the shank to fit over the opposite flat sides of the ferrule.

When soldered thereto the shank is rigidly connected with the ferrule and the 110 handle is rigidly connected with the brush.

By my process the tuft of bristles is

shaped to fit snugly within the ferrule by holding them in a suitable mold, while their butts are glued together until the glue sets and hardens sufficiently to hold the bristles 5 in a proper position while fitting them within the ferrule.

It will be seen from the above description that the proper connection of the cap with the ferrule is effected by making them 10 of perfectly uniform shape, and soldering them together before the ferrule is deformed by inserting bristles therein.

I am aware that a metallic ferrule and handle have been made in one piece, and 15 also a cap in one piece with a ferrule, and I therefore disclaim such construction.

It is also old to secure the edge of a cap to a flat shell of the same shape as the ferrule and adapted to slip over and inclose 20 a great part of the ferrule before it is soldered thereto. This construction is adapted for manufacturing the heavier sizes of paint brushes, but it involves more parts than mine, which does not require a 25 reinforcing shell, and it is adapted for the

manufacture of the smaller sizes of paint brushes for which it has ample strength.

Having thus set forth the nature of the invention what is claimed herein is:

1. The method of making a flat paint brush, which consists in separately making a flat ferrule open at both ends, and a cap having a narrow flange adapted to fit over one end of the ferrule and provided with a hollow shank having integral tongues projected transversely to the flange, and finally soldering the flange of the cap and the tongues to the top end and sides of the ferrule respectively. 30

2. The combination, with a flat metallic ferrule, of a cap having a narrow flange upon its entire margin soldered to the entire periphery at one end of the ferrule, and a hollow metallic shank attached to the center of the cap and provided with integral tongues secured upon the opposite flat 35 sides of the ferrule. 40

In testimony whereof I have hereunto set my hand.

FRANK JOERGER.
